United States Patent Office

Des. 226,488
Patented Mar. 13, 1973

226,488

EMERGENCY TELEPHONE LIGHT

Fred G. Sinclair, 800 NE. 155th Terrace,
North Miami Beach, Fla. 33162

Filed Mar. 16, 1972, Ser. No. 249,490

Term of patent 14 years

Int. Cl. D14—03

U.S. Cl. D26—14 A

FIG. 1 is a top perspective view of an emergency telephone light showing my new design;

FIG. 2 is a bottom perspective view thereof;

FIG. 3 is a top perspective view thereof.

The broken lines are shown for illustrative purposes only and form no part of the claimed design.

I claim:

The ornamental design for an emergency telephone light, as shown and described.
